ABSTRACT

Compensating sheave apparatus for an elevator system having an elevator car, a counterweight, a hoisting machine, hoisting roping and compensating roping, wherein the compensating sheave apparatus includes a tensioning sheave for said compensating roping, a weight frame for said tensioning sheave, fixed guide rails for guiding the weight frame, and a safety device for coupling the weight frame to the guide rails only when the safety device is upwardly accelerated at a predetermined acceleration rate by the weight frame, and wherein the safety device includes coupling members, operative to grip the guide rails when the coupling members are actuated, and an inertial actuator having an inertial mass, operative to actuate the coupling means when the inertial mass senses the predetermined acceleration rate.

INVENTOR

COMPENSATING SHEAVE APPARATUS FOR ELEVATORS

The present invention relates to elevator systems, and particularly to an elevator system having a compensating rope sheave.

A conventional elevator system includes an elevator car, a counterweight, and a plurality of hoisting ropes, which suspend the elevator car and counterweight. The hoisting ropes pass over a hoisting sheave, which is disposed at the top of the hatchway. The elevator system also includes compensating ropes, which are suspended from the underside of the elevator car and counterweight in order to compensate for the unbalanced weight of the hoisting ropes. The compensating ropes have a compensating sheave unit, which is disposed at the bottom of the hatchway for guiding and tensioning the compensating ropes.

A conventional compensating sheave unit includes a compensating sheave, which guides the compensating ropes, a weight frame, which is connected to the sheave, a pair of fixed guide rails, which guide the weight frame, a safety block, which is connected to the weight frame, and a plurality of braking members, which are disposed between the safety block and the pair of guide rails. A conventional compensating sheave unit of this type is described in U.S. Pat. No. 1,789,008, issued Jan. 13, 1931.

The conventional compensating sheave unit ties down the compensating ropes and assures that the car, counterweight and ropes function as a closed system. In this way, deceleration forces, which are applied to the system, act on the total mass of the system. In addition, impact force, which the counterweight applies to the hoisting ropes and which is caused by the sudden rise and fall of the counterweight when the descending car is suddenly decelerated, is minimized.

The conventional compensating sheave unit also has a pair of coil springs, which are disposed between the safety block and the weight frame. These springs permit a limited upward movement of the weight frame relative to the safety block when the safety block grips the guide rails. This movement takes care of some of the longitudinal shrinkage in the hoisting and compensating ropes caused by changes in the temperature and humidity. However, in some elevator installations, the limited movement permitted by the coil springs is insufficient to take care of all of the rope shrinkage so that the rope stress is increased. For example, in a high-rise elevator installation in an air-conditioned building, if the air conditioning is shut off over a weekend, a relatively large increase in humidity can occur. This causes the ropes to swell in diameter thereby causing a substantial rope shrinkage in length and resulting rope stress.

In accordance with one embodiment of the present invention, rope stress due to such rope shrinkage is eliminated by providing a safety apparatus including a safety block, which is connected to the weight frame, braking members, which are mounted on the safety block for engaging the guide rails, and an inertial actuator, which is mounted on the safety block, and which senses an acceleration force applied thereto, and which applies the braking members to the guide rails only upon sensing a predetermined acceleration force. In this way, when the compensating ropes exert a predetermined acceleration force upon the sheave unit, the braking members are applied, but when the compensating ropes exert a rope shrinkage force on the sheave unit, or an acceleration force less than the predetermined acceleration force thereon, the braking members are not applied. Thus, the compensating sheave unit can move up or down without restraint to follow the rope shrinking and rope expansion. Also, the compensating sheave unit can grip the guide rails in order to tie down the compensating ropes when the elevator car is decelerated at a predetermined deceleration rate so as to assure that the car, counterweight and ropes function as a closed system.

Accordingly, it is one object of the invention to provide an elevator system having a compensating rope sheave unit, wherein rope stress caused by rope shrinkage is minimized.

It is another object of the invention to provide an elevator system according to the aforementioned object wherein the

compensating sheave unit is actuated to fixedly tie down the compensating ropes only when the compensating ropes apply a predetermined acceleration force to the compensating sheave unit.

5 It is a further object of the invention to provide an elevator system according to the aforementioned objects wherein the compensating sheave unit includes a sheave frame, a separate safety brake apparatus connected to the sheave frame, and a separate inertial actuator that is operative to actuate the safety brake apparatus only upon sensing a predetermined acceleration force.

10 It is still another object of the invention to provide an elevator system according to the aforementioned objects wherein the compensating sheave unit includes adjusting means for changing the level of the predetermined acceleration force at which the safety brake apparatus is actuated.

15 According to the present invention, there is provided an elevator system, comprising, an elevator car, a counterweight, a hoisting machine, hoisting roping, compensating roping, a tensioning sheave for said compensating roping, a weight frame connected to said tensioning sheave, guide rail means for guiding said weight frame, a safety block connected to said weight frame and cooperating with said guide rail means, 20 coupling means mounted on said safety block and movable relative thereto, said coupling means being operative to grip said guide rail means when said coupling means is actuated, and an inertial actuator mounted on said safety block, said inertial actuator having an inertial mass, said inertial mass being 25 movable relative to said safety block for sensing the acceleration rate of said safety block, said inertial actuator being operative to actuate said coupling means when said inertial mass senses a predetermined acceleration rate.

30 Other objects of the invention will become apparent upon reading the following description and accompanying drawings, wherein like parts are designated by like numerals throughout the several views, and wherein:

35 FIG. 1 is a schematic elevation view of an elevator system having a compensating rope sheave unit embodying features 40 of the present invention;

40 FIG. 2 is an enlarged portion of FIG. 1;

45 FIG. 3 is a sectional view as taken along the line 3—3 of FIG. 2;

50 FIG. 4 is a sectional view as taken along the line 4—4 of FIG. 3;

55 FIG. 5 is a sectional view as taken along the line 5—5 of FIG. 4;

60 FIG. 6 is a sectional view as taken along the line 6—6 of FIG. 5;

65 FIG. 7 is a sectional view as taken along the line 7—7 of FIG. 5; and

70 FIG. 8 is a sectional view as taken along the line 8—8 of FIG. 5.

75 Referring to FIG. 1, one embodiment of the present invention is an elevator system 10. Elevator system 10 includes an elevator car 11, and a counterweight 12 for car 11. System 10 also includes an elevator hoisting machine sheave 13, a deflector sheave 14, and a plurality of hoisting ropes 15, which support car 11 and counterweight 12. System 10 also includes a plurality of compensating ropes 16, which connect to car 11 and counterweight 12, and a compensating sheave assembly 17, which guides compensating ropes 16.

Hoisting ropes 15 and compensating ropes 16 are connected to car 11 and counterweight 12 so as to form a continuous closed loop, which is supported by hoisting machine sheave 13. Compensating ropes 16 compensate for the unequal distribution of weight of the hoisting ropes 15 due to the movement of car 11 and counterweight 12. The total weight of the loop of ropes 15, 16 at any position of car 11 and counterweight 12 is distributed in approximately equal amounts on each side of hoisting machine sheave 13. Thus, the tractive effort of hoisting machine sheave 13 on hoisting ropes 15 is improved. In addition, compensating sheave assembly 17 is positioned within the bottom loop portion of

compensating ropes 16 in order to guide and tension ropes 15, 16 and in order to cause car 11, counterweight 12 and ropes 15, 16 to act as a unit mass during deceleration of car 11, as explained hereafter.

Sheave assembly 17 includes a compensating sheave 20, which guides compensating ropes 16, a weight frame 21, which is connected to compensating sheave 20, a pair of guide rails 22, 23, which guide frame 21, and a safety apparatus 24, which fixedly couples and secures frame 21 to guide rails 22, 23 when the upward acceleration rate of the safety apparatus 24 exceeds a predetermined rate of acceleration.

Counterweight 12 normally applies an upward acceleration force through compensating ropes 16 to sheave assembly 17 when car 11 is decelerated during downward movement of car 11. When sheave assembly 17 is upwardly accelerated by such force at a predetermined acceleration rate, sheave assembly 17 automatically grips rails 22, 23 as explained hereafter. In this way, the upward movement of sheave assembly 17 is minimized, and car 11, counterweight 12, hoisting ropes 15 and compensating ropes 16 decelerate substantially as a unit mass. In addition, the upward movement and subsequent unrestrained, downward fall of counterweight 12 is minimized, so that stresses in hoisting ropes 15 are minimized.

In addition, when humidity and temperature changes cause a longitudinal shrinkage in ropes 15, 16, the rope shrinkage forces resulting therefrom, which have substantially no acceleration rate, are relieved by an upward movement of sheave assembly 17 relative to rails 22, 23. Thus, stresses in ropes 15, 16 caused by rope shrinkage forces are also minimized.

Compensating sheave 20 is journaled on a shaft 25, which is fixedly connected at the ends thereof to frame 21. Frame 21 is guided by rails 22, 23 for vertical movement of frame 21 relative to the rails. Sheave 20 is supported by frame 21 for rotation of sheave 20 relative to frame 21. In this way, compensating ropes 16 are guided by sheave 20 as car 11 and counterweight 12 move relative to each other. In addition, because sheave 20 is carried by ropes 16 and frame 21 is carried by sheave 20, the weight of frame 21 and sheave 20 act to tension ropes 16.

Frame 21 includes a pair of wall members 30, 31, which are connected together by bolt connectors 32, or the like. Wall members 30, 31 are symmetrically disposed about an assembly joint 33, and are journaled on shaft 25, and are disposed on opposite sides of sheave 20. Wall 30 has a pair of parallel guide bars 34, 35, which are fixedly connected thereto and which receive guide rail 22 therebetween. Wall 31 also has a corresponding pair of parallel guide bars 36, 37, which are fixedly connected thereto and which receive guide rail 23 therebetween.

Guide rails 22, 23 are fixedly connected at the lower ends thereof to respective support members 38, 39, which rigidly support guide rails 22, 23. Rail 22 (FIG. 4) has opposite bearing surfaces 40, 41 for guiding bars 34, 35; and rail 23 has similar opposite bearing surfaces 42, 43 for guiding its bars 36, 37.

Safety apparatus 24 includes a crosshead or block assembly 44, which is disposed between rails 22, 23, and includes a pair of braking members 45, 46, which clamp and secure block assembly 44 to rails 22, 23 when actuated. Apparatus 24 also includes an inertial actuator 47, which actuates braking members 45, 46 only when block assembly 44 is upwardly accelerated at the predetermined acceleration rate by the acceleration force from compensating ropes 16.

Block assembly 44 includes a pair of end block portions 49, 50, and a pair of cover plates 51, 52. Plates 51, 52 are connected to block portions 49, 50 by respective connector bolts 53, 54 for ease of assembly. Cover plates 51, 52 respectively have adjacent end slots 55, 56 on one side thereof, which receive rail 22, and adjacent end slots 57, 58 on the other side thereof, which receive rail 23 for guiding block assembly 44 along rails 22, 23.

Block assembly 44 has a pair of studs 59, 60, which are fixedly connected at the bottom ends thereof to frame 21 and which are slidably connected to block assembly 44. Studs 59, 60 guide frame 21 for movement of frame 21 relative to block assembly 44. Studs 59, 60 have respective compression springs 61, 62, which are concentric therewith. Studs 59, 60 respectively extend through bottom aperture 63 and top apertures 65, 66, which are disposed in cover plates 51, 52. Studs 59, 60 are fixedly connected at the lower ends thereof to a lower stop plate 67, which is also fixedly connected to frame 21; and studs 59, 60 are connected at the upper ends thereof to an upper stop plate 68, which limits the amount of movement of frame 21 relative to block assembly 44. Springs 61, 62 respectively extend through apertures 63, 65, and extend between cover plate 52 and stop plate 67. With this construction of block assembly 44, the movement of frame 21 relative to block assembly 44 is guided by studs 59, 60, and the extent of movement of frame 21 toward block assembly 44 is limited by lower stop plate 67, and the extent of movement of frame 21 away from block assembly 44 is limited by upper stop plate 68.

Springs 61, 62, which are alike, preferably have a high enough total spring rate to transmit the predetermined acceleration force from frame 21 to block assembly 44 immediately before block assembly 44 is clamped to rails 22, 23 by braking members 45, 46. Springs 61, 62 also preferably have a low enough spring rate to be compressed sufficiently by the predetermined acceleration force to permit frame 21 to contact block assembly 44 immediately after block assembly 44 is clamped to rails 22, 23 by braking members 45, 46.

End block 49 has an outer face 69, which has a recess 70 that receives guide rail 22. Recess 70 has oppositely facing sidewalls 71, 72, which are disposed on opposite sides of guide rail 22. Sidewall 71 has a vertical surface 73, which is disposed substantially parallel to its adjacent rail surface 40. Sidewall 72 has an inclined cam surface 74, which is inclined relative to its adjacent rail surface 41. Cam surface 74 cooperates with braking member 45 to lock end block 49 to rail 22 as explained hereafter.

Sidewall 71 supports a bearing plate 75, which is disposed between rail surface 40 and sidewall surface 73. Sidewall 71 also has an aperture 76, which has a pin 77 disposed therein that engages plate 75. Aperture 76 also has a compression spring 78 disposed therein, which engages pin 77 so that spring 78 urges pin 77 against plate 75. In this way, plate 75 is urged against rail surface 40 and the edges of end slots 55, 56 are urged against the opposite rail surface 41 for positioning and aligning end block 49 relative to rail 22. Sidewall 71 also has a spring retainer plate 79 bolted thereto, which closes one end of aperture 76. Plate 75 guides and supports pin 77 and retains spring 78 in aperture 76; and plate 75 is removable for ease of installation of spring 78.

End block 50 also has a corresponding outer face 80, which has a recess 81 that receives guide rail 23. Recess 81 also has opposite sidewalls 82, 83. Sidewall 82 has an inclined cam surface 84, and sidewall 83 has a vertical surface 85. Sidewall 83 has a bearing plate 86, which engages rail surface 43, and has an aperture 87, which receives a pin 88 that engages plate 86. Aperture 87 has a compression spring 89 that engages pin 88 urging pin 88 against plate 86 and urging plate 86 against rail surface 43. Sidewall 83 also has a removable spring retainer plate 90 closing one end of aperture 87. Springs 78, 89, which are alike, preferably have a nominal spring rate, which is high enough to assure that plates 75, 86 continually engage rails 22, 23 whereby noise caused by repetitive contact between block assembly 44 and rails 22, 23 is minimized. Springs 78, 79 provide a nominal friction between block assembly 44 and rails 22, 23, and studs 59, 60 allow some movement of frame 21 relative to block assembly 44, so that frame 21 can move up or down relative to block assembly 44 for a nominal distance without moving block assembly 44.

Braking members 45, 46, which are rollers, are respectively disposed adjacent to cam and rail surfaces 74, 41 and 84, 42,

for coupling rails 22, 23 to end blocks 49, 50. Rollers 45, 46 respectively bear against their adjacent rail surfaces 41, 42 and are normally separated, when not actuated, from their adjacent cam surfaces 74, 84 by respective gaps 91, 92. When rollers 45, 46 are actuated at the predetermined acceleration, rollers 45, 46 are simultaneously urged by actuator 47 to engage respective cam surfaces 74, 84. Such engagement causes rollers 45, 46 to become wedged between their adjacent surfaces 74, 41 and 84, 42. A slight upward movement of end blocks 49, 50 relative to rails 22, 23, which occurs simultaneously therewith, causes rollers 45, 46 to become tightly wedged between surfaces 74, 41 and 84, 42. In this way, block assembly 44 is rigidly coupled and secured to rails 22, 23 by rollers 45, 46. In addition, when rollers 45, 46 bear against respective rails 22, 23 on one side thereof, plates 75, 86 bear against respective rails 22, 23 on the exact opposite side thereof so that eccentric forces and moments on rails 22, 23 and on end block portions 49, 50 are avoided.

Actuator 47 includes a torque shaft 100, which interconnects rollers 45, 46 for simultaneous movement thereof, an inertial mass 101, which is eccentrically connected to torque shaft 100 for simultaneously actuating rollers 45, 46, and a restraining mechanism 102, which selectively locks torque shaft 100 for restraining inertial mass 101 from actuating the rollers 45, 46, except when block assembly 44 is accelerated at the predetermined acceleration rate.

Shaft 100, which has an axis of rotation 103, includes an integral radial arm 104, which is disposed near the middle of shaft 100 and which is fixedly connected to inertial mass 101 for angular displacement of mass 101 about axis 103. Shaft 100 also includes a pair of integral radial arms 105, 106, which are disposed near the axially outer ends thereof and which are respectively connected to a pair of links 107, 108. Links 107, 108 are pivotally connected at their radially inner ends to arms 105, 106 and are fixedly connected at their radially outer ends to respective roller pins 109, 110. Pins 109, 110, which are substantially parallel to axis 103, are respectively journaled in rollers 45, 46 for rotary movement of rollers 45, 46 about pins 109, 110 when rollers 45, 46 roll on rail surfaces 41, 42. Arms 105, 106 extend radially outwardly from shaft axis 103, and links 107, 108 extend radially outwardly from end arms 105, 106 for angular displacement of rollers 45, 46 about axis 103 when actuated by shaft 100. In this way, inertial mass 101 and rollers 45, 46 are eccentrically connected to shaft 100 for simultaneous transfer of force and simultaneous engagement of rollers 45, 46. Thus, when inertial mass 101 is angularly displaced about axis 103 relative to block assembly 44 at the predetermined acceleration rate, the acceleration force acting upon inertial mass 101 is simultaneously transferred to rollers 45, 46. In addition, rollers 45, 46 simultaneously engage cam surfaces 74, 84, so that sloping or tilting of block assembly 44 relative to rails 22, 23 is minimized.

Shaft 100 is mounted on a pair of support bars 111, 112, which are fixedly connected to cover plates 51, 52. Bars 111, 112, which are spaced apart, have respective bearings 113, 114, in which shaft 100 is journaled for rotation of shaft 100 relative to block assembly 44.

With this construction, inertial mass 101 can apply upon shaft 100 an actuating torque, which is proportional in amount to the amount of the predetermined acceleration rate applied to block assembly 44. Restraining means 102 can also apply upon shaft 100 a restraining torque, which acts counter to the actuating torque and which is substantially constant in amount, as explained hereafter. When block assembly 44 is accelerated at the predetermined acceleration rate, the actuating torque corresponding thereto, which exceeds the restraining torque, causes shaft 100 to rotate. When shaft 100 rotates, inertial mass 101 then applies its actuating torque upon rollers 45, 46 urging rollers 45, 46 against cam surfaces 74, 84. At the same time, the slight upward movement of block assembly 44 causes rollers 45, 46 to become tightly wedged between surfaces 73, 74 and 84, 85. In this way, block assembly 44 is secured to guide rails 22, 23 when block as-

sembly 44 is upwardly accelerated at the predetermined acceleration rate.

Restraining mechanism 102, which is a latching type of device, includes a catch bar 120, which is fixedly connected to shaft 100, and a latch pin 121, which is received in a cylinder 122 that is fixedly connected to support bar 111.

Latch pin 121, which is slidably received within cylinder 122 for axial displacement relative thereto, has an enlarged head portion 123 at one end thereof having a pointed tip portion 124, which projects from cylinder 122 and which engages a notch 125 in catch bar 120. Latch pin 121 also has an elongate shank portion 126, which projects from the other end of cylinder 122 and which has an assembly nut 127 threaded thereon for ease of assembly of latch pin 121 and cylinder 122.

Cylinder 122, which is a hollow member that has internal threads, receives an adjusting screw 128 forming the end wall thereof. Cylinder 122 also receives a compression spring 129, which is disposed between adjusting screw 128 and head portion 123 for urging latch pin 121 in any axially outward direction. Adjusting screw 128 is axially adjustable relative to cylinder 122 for adjusting the spring rate of spring 129. Adjusting screw 128, which has an aperture 130 at the center thereof that receives shank portion 126, is disposed between spring 129 and assembly nut 127 for guiding the movement of latch pin 121.

With this construction, when tip portion 124 is received in notch 125 and bears against catch bar 120, assembly nut 127 on latch pin 121 is axially displaced from adjusting screw 128, so that spring 129 applies its axial spring force through tip portion 124 to catch bar 120. However, when tip portion 124 is not received in notch 125 and does not engage catch bar 120, assembly nut 127 bears against adjusting screw 128 so that spring 129 applies its axial spring force upon adjusting screw 128.

When tip portion 124 is received in notch 125 and when inertial mass 101 applies its actuating torque on shaft 100, notch 125 applies a transverse force against tip portion 124. Spring 129 exerts against tip portion 124 an axial force, which is proportional to the spring rate. Tip portion 124 exerts a transverse reaction force against notch 125 that causes a restraining torque on shaft 100. When the actuating torque exceeds the restraining torque, and the actuating force upon latch pin 121 exceeds the reaction force therefrom, spring 129 is compressed and latch pin 121 is deflected inwardly. As latch pin 121 is deflected inwardly, shaft 100 and catch bar 120 rotate, catch bar 120 is disengaged from latch pin 121, and the restraining torque on shaft 100 ceases. The actuating torque is thereafter directly transmitted from inertial mass 101 through shaft 100 to rollers 45, 46. In this way, restraining mechanism 102 releases rollers 45, 46 when the predetermined acceleration rate is applied to safety apparatus 24. In addition, restraining mechanism 102 can be adjusted by turning screw 128 in order to change the level of the predetermined acceleration rate at which shaft 100 and rollers 45, 46 are released.

Apparatus 24 also has a switch device 131. Switch 131 includes a body portion 132, which is fixedly mounted on block assembly 44, and a spring-biased tripper pin 133, which is slidably mounted on block assembly 44 for movement of tripper pin 133 relative to body portion 132 for actuating body portion 132. Tripper pin 133 has an end portion 134, which is disposed between block assembly 44 and weight frame 21. End portion 134 is arranged to engage weight frame 21, and to thereupon actuate body portion 132, only when weight frame 21 engages block assembly 44.

Switch 131 is actuated only when the predetermined acceleration force displaces inertial mass 101 relative to block assembly 44 thereby clamping rollers 45, 46 to rails 22, 23, and only when the predetermined acceleration force continues for a long enough time interval so that frame 21 compresses springs 61, 62 and engages block assembly 44 thereby actuating switch tripper pin 133. In this way, switch 131 pro-

vides a useful indication, which preferably is used to stop car 11, and which indicates the occurrence of said type of acceleration force.

In operation, compensating sheave assembly 17 follows an operating sequence. When an upward rope shrinkage force or upward acceleration force is applied to compensating sheave assembly 17 by compensating ropes 16, the following operating sequence occurs:

1. When the upward force is applied to compensating sheave assembly 17 by compensating ropes 16, the upward force is transmitted from sheave 20 through sheave shaft 25 and frame 21 and springs 61, 62 to block assembly 44.
2. If the upward force is a rope shrinkage force, which has substantially no acceleration rate, block assembly 44 is not accelerated upwardly and inertial mass 101 is not urged downwardly relative thereto. Thus, if the upward force is a rope shrinkage force, the inertial mass 101 does not apply an actuating force urging compensating sheave assembly 17 to grip rails 22, 23, and compensating sheave assembly 17 can move upwardly relative to rails 22, 23 to automatically relieve the rope shrinkage force in ropes 16.
3. If the upward force is an acceleration force, block assembly 44 is accelerated upwardly at a substantial acceleration rate thereby causing a downward force on inertial mass 101 and an actuating torque on shaft 100. The actuating torque on shaft 100 causes a direct force from catch bar 120 to latch pin tip 124.
4. If the acceleration rate of block assembly 44 equals or exceeds a predetermined acceleration rate, spring 129 compresses and latch pin 121 deflects inwardly thereby releasing catch bar 120 to permit an angular displacement of shaft 100. This is because the spring rate of spring 129 is proportional to the level of the predetermined acceleration rate.
5. Thereafter, the actuating torque is transmitted through shaft 100 and end arms 105, 106 to rollers 45, 46 thereby displacing rollers 45, 46 through gaps 91, 92 into engagement with cam surfaces 74, 84. Simultaneously, block assembly 44 and its cam surfaces 74, 84 move upwardly wedging rollers 45, 46 between surfaces 41, 74 and 42, 84. In this way, when ropes 16 apply a predetermined acceleration force to sheave unit 17, block assembly 44 is clamped to rails 22, 23, but when ropes 16 apply a lesser acceleration force or a rope shrinkage force thereto, block assembly 44 is not clamped to rails 22, 23.

In summary, the present invention provides an elevator system having a compensating rope sheave unit, wherein rope stress caused by rope shrinkage is minimized, wherein the compensating sheave unit is actuated to fixedly tie down the compensating ropes only when the compensating ropes apply a predetermined acceleration force to the compensating sheave unit, wherein the compensating sheave unit includes a sheave frame and a separate brake apparatus connected to the sheave frame and a separate inertial actuator that is operative to actuate the safety brake apparatus only upon sensing the predetermined acceleration force, and wherein the compensating sheave unit includes adjusting means for changing the level of the predetermined acceleration force at which the safety brake apparatus is actuated.

While the present invention has been described in a preferred embodiment, it will be obvious to those skilled in the art that various modifications can be made therein within the scope of the invention. For example, one such modification within the scope of the invention is indicated hereafter. Braking members 45, 46 can be a pair of pawls instead, which are pivotally mounted on block assembly 44 and which engage respective tooth recesses in guide rails 22, 23. Also, actuator 47 can comprise a linkage instead, which is connected to the pawls for simultaneous movement thereof, a spring mechanism, which urges the pawls into engagement with the tooth recesses, a latching device, which engages the linkage to

restrain movement of the linkage and thereby prevent engagement of the pawls with the tooth recesses, and an inertial mass, which is connected to the latching device for selectively releasing the latching device. With such construction, engagement of the pawls with the tooth recesses is caused when the inertial mass senses a predetermined acceleration rate. In addition, another example of a modification within the scope of the invention is indicated hereafter. Restraining mechanism 102 can comprise spring means instead, which interconnects inertial mass 101 and block assembly 44, and can comprise an adjustable connection, which connects one end of the spring means to block assembly 44. Therefore, it is intended that the invention not be limited to the particular embodiment and arrangement which has been described.

15 What is claimed is:

1. In an elevator system comprising an elevator car, a counterweight, a hoisting machine including a rotatable traction sheave, hoisting ropes extending from a fastening at the top of said car upwardly over said sheave and downwardly to a fastening atop said counterweight, a tensioning sheave, compensating ropes extending downwardly from a fastening at the bottom of said car, under said tensioning sheave and upwardly to a fastening at the bottom of said counterweight, a weight frame connected to said tensioning sheave, guide rails guiding movement of said weight frame and tensioning sheave, a safety block connected to said weight frame, a pair of coupling members mounted on said safety block and movable relative thereto when actuated to grip said guide rail means, inertial actuator means including an inertial mass mounted on said safety block and movable relative thereto, and connecting means interconnecting said inertial actuator means and said coupling members, said inertial actuator including a restraining means, said restraining means being arranged to apply a substantially constant restraining force to said connecting means for preventing movement of said pair of coupling members, said restraining means being operative to remove said restraining force from said connecting means for releasing said connecting means when the inertial mass and said safety block are accelerated at a rate equal to or in excess of a predetermined acceleration rate.
2. An elevator system as claimed in claim 1, wherein said restraining means has adjusting means for changing the amount of said restraining force.
3. An elevator system as claimed in claim 2, wherein said connecting means includes a shaft supported by said safety block for rotation relative thereto, and wherein said pair of coupling members and said inertial mass are eccentrically connected to said shaft.
4. An elevator system as claimed in claim 3, wherein said restraining means includes, a latching mechanism mounted on said safety block, and a catch means mounted on said shaft and arranged to cooperate with said latching mechanism.
5. An elevator system as claimed in claim 4, wherein said latching mechanism includes, a cylinder mounted on said safety block, a latch pin disposed in said cylinder for displacement relative thereto, and an elongate compression spring disposed in said cylinder and arranged to urge said latch pin outwardly from said cylinder for applying a restraining force against said catch means.
6. An elevator system as claimed in claim 5, wherein said cylinder includes, a fixed portion which engages one end of said compression spring, and an adjustable portion which engages the other end of said compression spring, said adjustable portion being adjustably movable relative to said fixed portion for changing the spring rate of said compression spring.

7. An elevator system as claimed in claim 3, wherein said safety block has opposite end portions having respective cam surfaces respectively facing said guide rails, and wherein said coupling members are a pair of rollers, and wherein said shaft has arm portions respectively connected to said rollers, said arm portions being arranged to urge said rollers against said cam surfaces and said guide rails adjacent thereto when said shaft is actuated.

8. An elevator system as claimed in claim 7, wherein said block end portions have recesses respectively receiving said guide rails, each said recess having first and second sidewalls disposed on opposite sides of the guide rail adjacent thereto, said first sidewalls having respective surfaces inclined to the guide rails for forming the cam surfaces.

9. An elevator system as claimed in claim 8, wherein each end portion has a bearing member disposed between the second sidewall and the guide rail adjacent thereto, and wherein the second sidewall has spring means supported therefrom urging the bearing member against the guide rail.

10. An elevator system as claimed in claim 3, wherein said weight frame is connected to said safety block by slideable connecting means, said slideable connecting means being arranged to permit a limited amount of travel of said weight frame relative to said safety block.

11. An elevator system as claimed in claim 10, including switch means mounted on said safety block, said switch means having a tripper portion arranged to engage the weight frame when the weight frame engages the safety block.

12. A compensating sheave apparatus for an elevator comprising, a compensating sheave, a shaft on which said sheave is journaled, a weight frame journaled on said shaft, fixed guide means constraining movement of said compensating sheave and said weight frame, and a safety device connected to said weight frame and responsive to movement of said frame and compensating sheave at a rate of acceleration in excess of a predetermined rate to fasten said frame and sheave to said fixed guide means, wherein said guide means includes a pair of guide rails, and said safety device includes a safety block disposed between said guide rails for cooperation therewith,

said safety block being connected to said weight frame for limited travel relative thereto, coupling means mounted on said safety block and movable relative thereto, said coupling means being operative when actuated to grip said guide rails, and an inertial actuator having an inertial mass mounted on said safety block and movable relative to said block, said inertial actuator being held inoperative to actuate said coupling means until said inertial mass senses a rate of acceleration in excess of said predetermined acceleration rate.

10 13. A compensating sheave apparatus as claimed in claim 12, wherein said safety block has resilient means disposed between said safety block and said weight frame, and said safety block has a pair of end portions having respective recesses receiving said guide rails, each said recess having a sidewall having a cam surface inclined to said guide rail adjacent thereto; and wherein said coupling means includes a pair of rollers respectively disposed in said recesses between the cam surfaces and guide rails; and wherein said actuator includes a shaft rotatably mounted on said safety block and connected to said inertial mass and includes a restraining mechanism mounted on said safety block for restraining said shaft, said shaft having respective arm portions connected to said inertial mass and to each of said rollers, said restraining mechanism including a cylinder mounted on said safety block and a latch pin disposed in said cylinder and an elongate spring disposed in said cylinder for urging said latch pin into latching engagement with said shaft, said cylinder having an adjustable wall portion engaging said spring for adjusting the spring rate thereof.
